UNITED STATES PATENT OFFICE.

GEORGE J. L. JANES AND JOSEPH J. LANZIT, OF CHICAGO, ILLINOIS.

PACKAGE FOR ICE-CREAM AND THE LIKE.

No. 892,159.

Specification of Letters Patent.

Patented June 30, 1908.

Application filed May 7, 1906. Serial No. 315,504.

To all whom it may concern:

Be it known that we, GEORGE J. L. JANES and JOSEPH J. LANZIT, citizens of the United States of America, residing at Chicago, in the county of Cook and State of Illinois, have invented certain new and useful Improvements in Packages for Ice-Cream and the Like, of which the following is a specification.

13 Our invention consists in certain improvements in packages for ice-cream and the like, and is fully described and explained in the specification and shown in the accompanying drawings, in which

15 Figure 1 is a perspective view of our improved package closed; Fig. 2 is a perspective view showing the outer wrapper and the outer box opened, a portion of the outer box being broken away to show the interior arrangements of the parts; Fig. 3 is a front elevation of the package partly broken away to show the interior construction; Fig. 4 is a section in the line 4—4 of Fig. 3; and Fig. 5 is a perspective view of one of the spacers hereinafter described.

Referring to the drawings, A, represents a brick of ice-cream, or other similar substance, which when packed must be protected from heat. In practice this brick is placed within 30 an interior box, B, preferably of the folded pasteboard type in common use at the present time for packing ice-cream and similar substances, the brick being first preferably wrapped in paraffined paper to protect the 35 box from the moisture of the brick and also to render the brick non-adherent to the walls of the box. The inner box, B, is closed and placed upon a spacer, C, of pasteboard or the like, the same comprising a flat 40 central portion, c, of the dimensions of the bottom of the box, downwardly projecting flaps, c¹, along the four sides and upwardly projecting ears, c², struck up from the material of the spacer, one on each side thereof.

45 The four ears, c², lie outside the inner box, B, and prevent movement of the same with respect to the spacer, C. The spacer, C, with the box, B, upon it is next placed within an outer box, D, also preferably of pasteboard 50 of any of the well-known folding types, the form here shown having a rectangular body, d, a cover, d¹, end flaps, d², and a front flap, d³. The cover can be swung down over the open top of the outer box, when the end and 55 front flaps will completely envelop the open end, preventing the entrance of air. When

the spacer with the inner box upon it is inserted within the outer box, the weight of the inner box and its contents tends to force the side flaps, c¹, of the spacer outwards, but 60 their outward movement is presently arrested by engagement with the side walls of the outer box, at which time the side flaps lie at an angle of about forty-five degrees, with the side walls of the outer box as illustrated in Fig. 4, thereby supporting the inner box centrally with respect to the outer box and well above the bottom thereof. After the insertion of the inner box and the spacer, C, a second spacer, E, similar to the spacer, 70 C, is placed upon the top of the box in an inverted position, the side flaps of this spacer running to the upper edges of the outer box. The cover of the outer box is closed, after the second spacer is in position. Thereupon the 75 outer box is wrapped in a paper wrapper, F, preferably of wax or paraffined paper, and also preferably secured to the outer box at the bottom thereof for convenience in packing.

It is common practice for the manufacturers of brick ice-cream to furnish it to retailers, commonly drug-store proprietors, done up in pasteboard boxes like the inner boxes herein shown and packed in ice for 85 safe keeping. However, as soon as these bricks thus packed are removed from the ice, they melt rapidly, and it is practically necessary that a single brick of ice-cream bought in a pasteboard box in this way be consumed 90 a very short time after it is removed from the ice, or it will be entirely melted, if kept in a room of average indoor temperature or if the weather be warm. This fact has interfered very seriously with the sale of brick ice-cream and has made it necessary to pack the individual bricks to be delivered to the consumer in ice, thus necessitating an ice receptacle which must be called for by the dealer, with consequent added delivery calls and 95 hence higher prices for the goods.

The purpose of our present invention is to devise a package for brick ice-cream particularly adapted to receive these cheaply packed bricks, such as are sold in most large 105 cities, for about twenty-five cents, and which will protect them from the action of heat to such an extent that they will be in proper condition for use after several hours. This result is accomplished in our device by supporting the inner box which contains the cream within an outer box, so that the inner

box is separated from the walls of the outer box on all sides by a layer of confined air the temperature of which is reduced by the frigid contents of the inner box. As will be readily understood, the temperature of this surrounding layer of chilled air must first be raised by the temperature of the atmosphere before the temperature of the contents of the inner box can be affected, and the melting or softening of such contents results. Thus the contents of the inner box is protected on all sides by a layer or sheath of dead air which is chilled by the frozen contents of such inner box thus greatly delaying the warming of the contents of the inner box.

Furthermore, we make the entire structure in such cheap form that it adds but little to the cost of the product, and also in such form that the outer boxes can be shipped flat to the retailer, so that the bricks can be removed when desired from the ice in which they are furnished, placed upon spacers which lie perfectly flat until they are ready to be used, and placed inside the outer boxes which can be instantly folded up from flat material for packing purposes. Under the conditions under which the ice-cream trade is carried on, this last feature is of great importance, for it is extremely desirable to furnish the outer boxes and spacers in compact and convenient form to the retailers at the same time having the manufacturer of the ice-cream furnish the inner boxes and inner paraffined wrappers as they do at present. The ordinary ice-cream-brick boxes are of standard size and form, and the retailer can purchase the outer boxes and spacers in quantities, using them for such of his customers as desire them, without using them in such cases as they are not desired, as, for instance, when the cream is desired for immediate use.

We realize that considerable variation is possible in the details of this construction, without departing from the spirit of our invention; therefore, we do not intend to limit ourselves to the specific form herein shown and described.

We claim as new and desire to secure by Letters Patent:—

1. The combination with two boxes, one within the other, of spacers formed from sheet-material and having portions bent toward the outside of the outer portion, and

other portions in contact with the inner box 55 whereby the inner box is supported out of contact with the walls of the outer box.

2. The combination with two boxes, one within the other, the inner being adapted to receive ice-cream or the like, of two 60 spacers formed of sheet-material, one above and one below the inner box, each of said spacers having portions extending to the edges of the outer box, and portions in contact with the inner box. 65

3. The combination with two boxes, one within the other, the inner being adapted to receive ice-cream or the like, of two spacers formed of sheet-material, one above and one below the inner box, each of said spacers 70 having portions extending to the edges of the outer box, portions in contact with the inner box, and other portions engaging the sides of the inner box.

4. The combination with an outer box, of 75 an inner box to receive ice-cream and the like, and spacers of sheet-material having flaps turned down along the edges and extending to the edges of the outer box and other portions turned up outside the walls of 80 the inner box.

5. The combination with a receptacle for ice-cream and the like, of a box of larger dimensions than the receptacle, said box being folded from a flat blank of pasteboard, 85 and two spacers likewise formed of flat blanks of pasteboard, each of which has flaps extending to the edges of said outer box, portions in contact with said receptacle, and ears extending up beside said receptacle to 90 secure it in place.

6. A box for packing pasteboard receptacles containing ice-cream and the like, comprising a box adapted to be folded up from a flat blank of pasteboard and two 95 spacers adapted to be folded from flat material, each of which has edges running to the corners of the completed box, and ears to engage the sides of the receptacle.

In witness whereof we have signed the 100 above application for Letters Patent at Chicago, in the county of Cook and State of Illinois, this 30 day of April, A. D. 1906.

GEORGE J. L. JANES.

JOSEPH J. LANZIT.
